UNITED STATES PATENT OFFICE.

DAVID H. HUNTER, OF DALLAS, TEXAS, ASSIGNOR TO SULLIVAN MACHINERY COMPANY, A CORPORATION OF MASSACHUSETTS.

CONTROL MECHANISM.

Application filed October 1, 1921. Serial No. 504,801.

My invention relates to control mechanisms and more particularly to control mechanisms for providing timed operation of pumping mechanism controlled thereby.

5 An object of my invention is to provide an improved controlling mechanism. Another object of my invention is to provide improved control mechanism for providing adjustable timing of the mechanism controlled thereby. A further object of my invention is to provide improved control mechanism controlling the supply and interruption of flow of power medium to a pumping mechanism controlled thereby. Another 10 object of my invention is to provide an improved control mechanism adapted automatically and continuously to control the operation of pumping mechanism controlled thereby. Further objects of my invention 15 will hereinafter appear.

In the accompanying drawings I have shown for purposes of illustration one form which my invention may assume in practice.

20 In these drawings,—

Fig. 1 is a view in elevation of the illustrative form of my improved control or timing mechanism employed in connection with a displacement pumping system.

25 Fig. 2 is a plan view on an enlarged scale of my improved control mechanism.

Fig. 3 is an enlarged elevation of my improved control mechanism per se showing the parts in the same relative position as 30 shown in Fig. 1.

Fig. 4 is an elevation of the mechanism shown in Fig. 3, the mechanism being viewed as if turned through 90° about a vertical axis.

35 Fig. 5 is a section on an enlarged scale corresponding to the section line 5—5 of Fig. 4.

Fig. 6 is a vertical longitudinal section through the power cylinder of my control mechanism, the view being taken on the line 40 6—6 of Fig. 4.

Fig. 7 is a vertical longitudinal section on the line 7—7 of Fig. 4, showing details of construction of the timing element per se 45 forming a portion of my timing or control mechanism.

For purposes of illustration I have shown my improved timing mechanism arranged for use in connection with a displacement 50 pumping system of a well known form. In

this system a compressor 1 supplies pressure fluid to a receiver 2 from which by way of a pipe 3 the fluid is adapted to be led to my improved control mechanism which is generally designated 4. Under the control 60 of this mechanism the fluid is distributed by branch lines 5 and 6 alternately to displacement tanks 7 and 8, the displacement tanks being filled with liquid during periods when the pressure is not being supplied to them, 65 by way of a supply line 9 whose communication with the tanks is controlled by check valves 10 and 11, and during the supply of pressure fluid to said tanks the liquid contained therein is discharged alternately past 70 check valves 12 and 13 to a discharge line 14.

By means of a valve mechanism best shown in Fig. 5, pressure fluid supplied from line 3 is conducted to a valve casing 16 cooperating with and forming a part of my improved timing mechanism. As previously indicated, the casing 16 communicates by pipes 5 and 6 (see Fig. 1) with the displacement tanks 7 and 8. In alignment with the supply pipe 3 is arranged an exhaust pipe 17. 80 Within the housing 16 is arranged a bore which may be conical or cylindrical as preferred, this bore being designated 18 and communicating by passages 19 and 20 respectively with fluid pressure supply line 3 85 and the vent line 17. The bore 18 also communicates by passages 21 and 22, which are disposed both to one side of the plane including the axis of the valve and perpendicular to a line drawn between the inlet and 90 discharge openings 19 and 20, with the lines 5 and 6 respectively. Attention is directed at this time to the fact that the passage 19 is of smaller flow area than the passages 21 and 22. The purpose of this will be shortly 95 explained.

Rotatably mounted within the bore 18 is a valve member 23 which is shaped to accurately fit said bore and which is cut away on opposite sides to provide flow passages 24 and 25 adapted in opposite positions of the valve to connect the ports 21 and 22 alternately with the ports 19 and 20. As shown in Fig. 5, it will be apparent that as the valve moves from a position in which either of the ports 21 or 22 is connected with the supply port 19, while the other is connected with the discharge port 20, to a reverse position, the ports 21 and 22 will be connected with each other through the passage 24, it 105 110

being noted that at the same time the passage 19 also communicates with said passage. However, by reason of the fact that the flow area of the ports 21 and 22 and passage 24 is greater than that of the port 19, there will be a considerable transfer of fluid from the port 22 to the port 21 or vice versa and so a saving in the quantity of fluid which must flow from the port 19 in filling up the volume 10 above the liquid level in the tank about to be discharged.

It will be noted that the valve 23 is herein provided with a square shank 26 (see Fig. 3) upon which is secured an operating lever 27, although it will be obvious that the valve may be operated by any other kind of operating member. Pivotaly connected to one end of the lever or arm 27 is a rod 28 extending in a substantially vertical direction and having secured thereon adjustable lock nuts 29 and 30 adapted to serve as abutments or collars for the rod 28 and to be engaged by means hereinafter described.

For the purpose of controlling movements 25 of the rod 28, I have provided improved actuating and timing mechanism comprising together with structure later described a cylinder 31 in which a piston 32 is vertically reciprocable, said piston being adapted to

30 raise a weight 33 upon upward movement thereof and to have its downward movement assisted by said weight. Between the top of said piston 32 and said weight 33 there is fixed a cross head 34 which is generally L-shaped in outline, (see Fig. 2) this cross-head being secured to the piston by means of a nut 35 threaded upon a stud not shown, upon whose upper end the weight 33 is likewise threaded.

40 Arranged parallel to the cylinder 31 is a dash-pot cylinder 36 in which a dash-pot piston 37 is reciprocable. The dash-pot piston 37 has a piston rod 38 which is secured by nuts 39 to the junction of the arms 45 of the L-shaped crosshead 34. It will be noted that the piston 32 is secured to said L-shaped cross head at a point about midway of the length of the larger arm of the latter. The dash-pot cylinder 36 is provided in a 50 lateral wall thereof with a longitudinally extending passage 41 communicating with the bore of the cylinder by four openings arranged respectively; one relatively near the top of the cylinder and designated 42, one practically at the bottom, designated 43, and a pair about mid-way between the ports 42 and 43 and separated by a space in the illustrative form shown somewhat longer than the thickness of the piston 37, these last 55 holes being designated 44 and 45 of which the port 45 is the lower. Intermediate between the ports 44 and 45 is a screw 46 which is adapted to be more or less projected into the passage 41 and so to limit the rate of flow through that portion of the passage in

which the screw is disposed. It will be evident that the dash-pot is filled with liquid to a point above the upper port 42.

From the construction described, it will be evident that the piston 37 may be moved quite freely upward until the port 45 is closed, the liquid, herein oil, simply bypassing through the port 45, passage 41 and port 43. After closure of the port 45 all liquid passing from the upper to the lower side of the piston 37 must pass by the screw 46 and accordingly there is a considerable retardation which may be varied by adjustment of the screw 46. When the piston has passed above the port 44, its movement may again take place quite freely as then liquid passing through the port 42 and down passage 41 may flow in behind the piston through the port 44. It will thus be seen that the piston may move quite rapidly adjacent the opposite ends of its travel, but for a space near the middle of its travel it is compelled to move quite slowly. During downward movement of the piston it can move rapidly until it reaches the port 44, must move slowly until the port 45 is opened by the upper surface of the piston, and thereafter may move rapidly until it reaches substantially the bottom of its cylinder.

As stated above, the upper end of the piston rod 38 is rigidly connected to the L-shaped crosshead at the angle of the latter and so the piston 37 must move as the piston 32 moves, and the rate of movement of the piston 32 is limited by the rate of possible movement of the piston 37. It should next be noted that a valve of the ordinary three-way type is arranged in a fluid pressure supply pipe 47 leading to a port 48 in the bottom of the cylinder 31, this valve being adapted in opposite positions to supply air beneath the piston 32, and, having cut off said air supply, to vent the bottom of the cylinder 31. As this valve is of the ordinary three-way type no specific illustration is believed requisite. The valve is provided with an operating arm or lever 49 to one end of which is connected a spring 50, the latter at its other end being connected to a vertically reciprocable rod 51. The rod 51 is reciprocable in guides 52 secured to the side of the dash-pot cylinder and these guides likewise serve as stops to be engaged by the other end of the lever 49, to determine the stationary positions of the valve. It will be clearly evident that as the rod 51 is raised the free end of the spring 50 will be moved upward until the tension is along a line making an angle with the longitudinal axis of the member 49 and lying above the latter. As a result the valve will be sharply thrown to an opposite position from that shown in Fig. 4, i. e. so that the air is cut off from the port 48 and the latter is connected with exhaust. The movements of the

rod 51 are determined by the engagement with adjustable collars or abutments 54 and 55 thereon by one branch, herein the shorter one, of the angular or L-shaped crosshead 34, it being evident from an inspection of Fig. 4 that the crosshead may move upward a considerable distance before beginning to move the valve 32 previously described, and causing the latter to be thrown only adjacent the upper end of its stroke. The extremity of the other arm of the L-shaped crosshead is perforated and through it extends the rod 28. As a result the valve 23 will be moved to its opposite positions by movements of the crosshead 34. By reason of the relatively rapid movement of the piston 32 as controlled by the dash-pot adjacent the ends of its travel, it will be evident that the valve 23 will be thrown quite rapidly, while being held stationary for a considerable period during the travel of the piston 32 along the middle portions of its path.

The mode of operation of this mechanism, it is believed, will already be very clear, but it may be more fully described as follows: Assume that there is air or other fluid under pressure in the pipes 47 and 3, and that the three-way valve is in a position corresponding to the illustration of the arm 49 in Fig. 4. Pressure will be supplied to the port 48 beneath the piston 32 and cause the latter to move upwardly raising the weight 33 with it. The piston will move quite rapidly for a short period and then as the dash-pot piston closes port 45, will be retarded for a space of time sufficient to permit the tank which is discharging to discharge and the tank which is filling to fill. After the port 44 is uncovered by the lower edge of the piston 37, the movement of the piston 32 will be quite rapid and as the latter reaches the upper end of its travel the crosshead 34 will strike the abutment 30 and shift the valve 23 to its opposite position, this being done fairly rapidly due to the small retardation by the dash-pot during that time. The piston will, however, continue to move sufficiently far to cause the rod 51 whose abutment 55 is engaged by the crosshead 34 at about the same time as the abutment 30 is engaged by the latter to be raised and under the action of the spring 50 reverse the position of the three-way valve, the supply of air then being cut off to the port 48 and a suitable vent opened. The piston 32 will then move downward due to the force of gravity, this action occurring relatively rapidly until the port 44 is closed, there being thereafter a certain delay, and thereafter the piston moving quite rapidly when the port 45 has been opened. As the piston approaches the bottom of its stroke the valve 23 will be shifted to the opposite position and the three-way valve will be reversed to

cause a re-admission of pressure beneath the piston 32.

While I have in this application specifically described one form which my invention may assume in practice, it will be understood that this form of the same is shown for purposes of illustration and that the invention may be modified and embodied in other forms without departing from its spirit or the scope of the appended claims.

What I claim as new and desire to secure by Letters Patent is:

1. A controlling mechanism comprising a valve, power actuating means therefor, and a self-contained fluid controlling means adapted to control said power means so that said valve is opened or closed relatively fast.

2. A controlling mechanism comprising a valve, power actuating means therefor movable in opposite directions, and a self-contained fluid controlling means adapted to perform substantially identical functions during either of said movements to control said power means so that said valve is opened or closed relatively fast.

3. A controlling mechanism comprising a valve, power actuating means therefor, and a liquid dash pot adapted to control said power means so that said valve is opened or closed relatively fast.

4. A controlling mechanism comprising power actuated means, valve mechanism adapted to be actuated thereby and to control power flow to said means and another supply of fluid, and means, including liquid control means adapted to control said power means, whereby said supply and power flow is adapted to be sequentially influenced relatively fast.

5. A self-contained controlling mechanism comprising a movable power actuated member, trigger mechanism for controlling power flow thereto, and means movable with said member and adapted to initially actuate said trigger mechanism.

6. A self-contained controlling mechanism comprising a power actuated member movable in opposite directions, trigger mechanism for controlling power flow thereto, and means movable with said member and adapted to initially actuate said trigger mechanism in either direction of movement thereof.

7. In a controlling mechanism, a controlling member movable along a predetermined path and in opposite positions thereof controlling a mechanism controlled thereby, means for causing said member to move in opposite directions respectively by gravity and by fluid pressure, and fluid means associated with said member for controlling the rate of movement thereof.

8. In a controlling mechanism, a controlling member movable between opposite positions to control the mechanism controlled

- thereby, means for supplying power to said member to effect opposite movements thereof, means associated with said member for controlling said first mentioned means, and means operative only during mid-travel of said member and associated with said member for controlling the rate of movement thereof.
9. In a controlling mechanism, a cylinder, a piston reciprocable therein, means for controlling the supply and exhaust of fluid to said cylinder to govern the movements of said piston, a controlling member controlled by movements of said piston, and a dash-pot controlling the rate of movement of said piston and retarding the same to a maximum degree adjacent the mid-travel thereof while permitting relatively uniform retardation in the initial portions of its travel, said first mentioned means being governed by movements of said piston.
10. A controlling mechanism comprising parallel cylinders, pistons movable in said cylinders and connected together, means for supplying pressure fluid to one of said cylinders to move its piston, means for retarding the movement of said other piston, and means controlled by the movements of said pistons for controlling the supply of operating fluid to said first mentioned piston and controlling a controlling means.
11. In a controlling mechanism, a controlling member, a piston, a cylinder in which said piston is reciprocable, operating connections between said piston and said controlling member, and liquid dash pot means associated with said piston for retarding movements of said piston at a time when said operating connections are idle and inoperative to retard movement of said piston when said operating connections are functioning.
12. Controlling mechanism comprising a controlling member, means for moving the same through a given cycle, said member at spaced points in said cycle governing the operation of mechanism controlled thereby, and means cooperating with said member and regulating its rate of movement during the middle portion of its travel between said points, which means exerts no influence on its travel at other portions of said cycle.
13. Controlling mechanism comprising a controlling member, means for moving the same through a given cycle, said means at predetermined positions in said cycle governing the operation of mechanism controlled thereby, and means cooperating with said member to regulate its rate of movement during the middle portion of its travel including a liquid dash pot.
14. Controlling mechanism comprising a controlling member, means for moving the same through a given cycle, said means at predetermined positions in said cycle gov-
- erning the operation of mechanism controlled thereby, and means cooperating with said member to regulate its rate of movement during the middle portion of its travel including a liquid dash pot offering substantially equal resistance to movement in opposite directions.
15. Controlling mechanism comprising a controlling member, means for moving the same through a given cycle, said member at spaced points in said cycle governing the operation of mechanism controlled thereby, means for regulating the rate of movement of said member including a liquid dash pot comprising a cylinder and piston and means forming a plurality of bypass passages arranged one adjacent either end of said cylinder and one near the middle of the cylinder, and means for controlling the rate of flow through said middle bypass passage.
16. Controlling mechanism comprising a controlling member, said member adjacent the ends of its path governing the operation of a mechanism controlled thereby, means for effecting opposite movements of said member, and means for controlling movements of said member arranged parallel thereto and comprising a liquid dash pot.
17. Controlling mechanism comprising a vertical cylinder, a weighted piston reciprocable therein, a controlling valve operative to supply pressure to and to exhaust pressure from a pair of tanks in alternate relation, valve means for controlling the supply and exhaust of pressure fluid to said cylinder, trigger valve gear for said last mentioned valve, and means movable with said piston to control both valve mechanisms.
18. Controlling mechanism comprising a pair of parallel cylinders angularly disposed to the horizontal, a weighted piston reciprocable in one of said cylinders, a dash pot piston reciprocable in the other of said cylinders, operative connections between said pistons, valve mechanism controlling the supply and exhaust of pressure fluid to said first mentioned piston and cylinder, separate valve mechanism for controlling supply and exhaust of fluid to a mechanism to be controlled, and means controlled by the reciprocation of said piston for mechanically actuating said valves.
19. In a controlling mechanism, a controlling member reciprocable in opposite directions by gravity and by fluid pressure, and means for controlling the opposite movements thereof including a single dash pot cylinder, a piston therein, means constituting a bypass adjacent the bottom of the cylinder, a bypass adjacent the top of the cylinder and a bypass adjacent the middle of the cylinder, said bypasses being so disposed that any movement of the dash pot

- piston will occasion fluid flow through at least one bypass, and means for regulating the rate of flow through one of said bypasses.
- 5 20. In a controlling mechanism, a controlling member reciprocal in opposite directions by gravity and by fluid pressure, and means for controlling the opposite movements thereof including a single dash pot
- 10 cylinder, a piston therein, and means constituting a bypass adjacent the bottom of the cylinder, a bypass adjacent the top of the cylinder and a bypass adjacent the middle of the cylinder, said bypasses being so disposed that any movement of the dash pot piston will occasion fluid flow through at least one bypass, and means for regulating the rate of flow through the middle bypass.
- In testimony whereof I affix my signature.

DAVID H. HUNTER.
